UNITED STATES PATENT OFFICE

LOUIS COHEN, OF WASHINGTON, DISTRICT OF COLUMBIA

RADIO SIGNALING

Application filed July 18, 1928. Serial No. 293,608.

(GRANTED UNDER THE ACT OF MARCH 3, 1883, AS AMENDED APRIL 30, 1928; 370 O. G. 757)

The invention described herein may be manufactured and used by or for the Government for governmental purposes without the payment to me of any royalty thereon.

6 This invention relates to the art of radio signaling and particularly to improvements in receiving systems of radio signals. The invention has for its object an improvement in methods and means for the reception of radio 10 signals by which a high degree of selectivity and freedom from interfering disturbances are secured.

In my copending patent application Serial Number 233,919, filed November 17, 1927, I 15 have described a novel method for selective signaling based on the use of a wave conductor interposed between the source where the signals are received and the detecting means. The wave conductor is one of distributed in- 20 ductance and capacity on which stationary waves are established by the received signals, the electrical length of the conductor being adjusted to an odd multiple of quarter wave lengths of the signals which are to be received.

25 At the nodal point of the stationary waves thus established on the conductor electrical leaks in the form of resistances or impedances to ground are introduced. The theory of the method and the principles of operation are 30 being fully discussed in the application referred to above.

The present invention utilizes the same principles but in a modified form securing thereby additional improvements in the selective 35 reception of radio signals.

The improvements contemplated in this invention will appear evident from the description and the discussion of the accompanying drawings which show typical embodiments 40 of the invention.

In the drawings—

45 Figure 1 is a diagrammatic view of an embodiment of the invention in which a quarter wave length coil is connected to the antenna and the receiving circuit system is placed in proximity to the wave coil;

Figure 2 is a modification of Figure 1 consisting in the introduction of an electrical leak from the antenna to ground;

50 Figure 3 is an other modification in which

a three-quarter wave length coil is used and two electrical leaks to ground;

Figure 4 is an arrangement similar to that of Figure 2 except that the adjustment of the wave conductor is effected by means of a vari- 55 able condenser;

Figure 5 is an embodiment of the invention similar to that shown in Figure 3 except for the means of adjusting the wave conductor which is accomplished by means of a single 60 variable condenser.

Having particular reference to the drawings in which the same numbers designate similar parts in all of the drawings; in Figure 1 the antenna designated by 1 is connected in series with the wave coil 2; in close proximity to the wave coil 2 is a metal plate 3 which is grounded at 4. A closed oscillatory circuit 5 comprising an inductance 65 and a variable condenser 17 associated with suitable detecting and amplification means of the usual types which are connected to the terminals 6 and 7, is placed in the proximity of the wave coil 2. With this arrangement 70 a high degree of selectivity in the reception 75 of radio signals is obtained. The principle of operation is as follows: The wave coil 2 is adjusted to a quarter wave length of the signals which are to be received; the adjustment is accomplished by the variation of 80 the distance separation of the grounded metal plate 3 from the wave coil 2, thereby varying the distributed capacity of the wave coil and thus effecting an adjustment to a quarter wave length for a particular signal 85 frequency. When this is accomplished a voltage rise is developed on the wave coil which in turn induces a high voltage on the closed circuit 5, which is again accentuated by the tuning of that circuit and thus a high 90

voltage is obtained at the terminals 6 and 7 which connect to the grid and filament of either a detector tube or a radio frequency amplifier tube in the usual manner. By this arrangement good selectivity in the reception 95 of radio signals is obtained because the adjustment of the wave coil 2 makes the antenna system highly discriminating in favor of the particular signal for which the system is in adjustment, building up a high 100

voltage for that signal only which is then transmitted through electro-static induction to the closed tuned circuit 5 and the associated detector and amplifier. Additional tuning, if desired, may be secured by the use of a tuned radio frequency amplifier.

The arrangement shown in Figure 2 provides for an additional improvement which consists in connecting the antenna 1 to ground 4 through an impedance 8 which may be in the form of an inductance, a capacity or a resistance. I have established mathematically and verified it experimentally that when the wave coil 2 is adjusted to be exactly 10 a quarter wave length or on odd multiple of quarter wave lengths of a particular signal, then for that signal the junction point 18 of the antenna and wave coil is practically at zero voltage and therefore grounding that point through an impedance has very little, if any effect, on the strength of the signal transmitted to the wave conductor; very little, if any of the signal current finds its way to ground through this leak connection. For any other signal, however, or any 15 irregular interfering electrical impulse as that due to static, the junction point 18 is no longer at zero potential, and a considerable portion of the signal energy will find 20 its way to ground through the leak 8; that is a considerable portion of the energy acting on the antenna is by-passed from the antenna to the ground thereby still further reducing interfering effects from undesirable 25 signals. This arrangement offers therefore a means for securing a very high degree of selectivity and freedom from static disturbances in the reception of radio signals.

In Figure 3 a modification is shown in 30 which a three-quarter wave length coil 9, 10 is used. The coil 9 is adjusted for a half wave length and coil 10 is adjusted for a quarter wave length. Voltage nodal points are established at the junction points 18 and 19 35 at which points electrical leaks to ground 8 and 13 are introduced. The adjustment of either 9 or 10 are accomplished through the variation of the separation distances of the grounded metal plates 11 and 12 from the 40 respective coils 9 and 10 varying thereby the distributed capacities of these coils. It is quite obvious that by this arrangement the selectivity of the system is still further enhanced. This arrangement is particularly 45 advantageous in the elimination of irregular 50 electric disturbances in accordance with the explanation given quite fully in my pending patent application referred to above.

This arrangement shown in Figure 4 is similar 55 to that of Figure 2 except that the adjustment of the wave coil 2 is effected by means of the variable condenser 14. The capacity of the wave coil depends on the capacity of the coil 2 to the metal plate 3 and 60 the capacity to ground through the variable

condenser 14. By varying therefore condenser 14 the capacity of the wave coil 2 is varied and an adjustment can therefore be made by this means.

The modification shown in Figure 5 differs 70 from the arrangement shown in Figure 3 only in that a common metal plate 15 in proximity to the wave coils 9 and 10 is used, and the adjustment of both wave coils 9 and 10 is simultaneously effected by the variation of 75 the single condenser 14 through which the metal plate 15 is connected to ground 4. The method of adjustment is the same as that described in connection with Figure 4.

Having thus described my invention what 80 I claim is—

1. In a system for the reception of radio signals comprising an antenna, a wave conductor connected in series therewith, the said wave conductor being adjustable to a quarter 85 wave length of the signals to be received, an oscillatory circuit placed in inductive relation to the said wave conductor, and means associated with said oscillatory circuit for detecting and amplifying said radio signals. 90

2. In a system for the reception of radio signals comprising an antenna, a wave conductor connected in series therewith, the said wave conductor consisting of a solenoidal coil, a grounded metal plate in close 95 proximity to the said solenoidal coil, the inductance and capacity per unit length and the length of the wave conductor being adjustable for a quarter wave length of the signals to be received, an oscillatory circuit 100 placed in inductive relation to said wave conductor, and means associated with said oscillatory circuit for detecting and amplifying said radio signals.

3. In a system for the reception of radio 105 signals comprising an antenna, a wave conductor connected in series therewith, said wave conductor consisting of a solenoidal coil, a grounded metal plate in close proximity to the said solenoidal coil, the inductance and capacity per unit length and the length of the wave conductor being adjustable for a quarter wave length of the signals to be received, the adjustment being effected 110 by varying the separation distance of the 115 grounded metal plate from said wave coil, an oscillatory circuit placed in inductive relation to said wave conductor, and means associated with said oscillatory circuit for detecting and amplifying said radio signals. 120

4. In a system for the reception of radio signals comprising an antenna, a wave conductor connected in series therewith, the said wave conductor consisting of a solenoid coil, a grounded metal plate in close proximity to 125 the said solenoidal coil, the inductance and capacity per unit length and the length of the wave conductor being adjustable for a quarter wave length of the signals to be received, the adjusting being effected by vary- 130

ing the separation distance of the grounded metal plate from said wave coil, an oscillatory circuit placed in electrostatic inductive relation to said wave conductor, and means 5 associated with said oscillatory circuit for detecting and amplifying said radio signals.

5. In a system for the reception of radio signals comprising an antenna, a wave conductor connected in series therewith, the said 10 wave conductor consisting of a solenoidal coil, a grounded metal plate in close proximity to the said solenoidal coil, the inductance and capacity per unit length and the length of the wave conductor being adjustable for a quarter wave length of the 15 signals to be received, the adjustment being effected by varying the separation distance of the grounded metal plate from said wave coil, a tuned oscillatory circuit placed in inductive relation to said wave conductor, and means associated with said oscillatory circuit for detecting and amplifying said radio signals.

6. In a system for the reception of radio 25 signals comprising an antenna which is grounded through an impedance, a wave conductor connected to the said antenna at the junction point where the antenna connects to the grounded impedance, the said wave conductor being adjustable to a quarter wave length of the signals to be received, a tuned oscillatory circuit associated in inductive relation to the said wave conductor, and means 30 associated with said oscillatory circuit for detecting and amplifying said radio signals.

7. In a system for the reception of radio 40 signals comprising an antenna which is grounded through an impedance, a wave conductor connected to the said antenna at a junction point where the antenna is connected to the grounded impedance, the said wave conductor being adjustable to a quarter wave length of the signals to be received, a tuned oscillatory circuit associated in inductive 45 relation to the said wave conductor, and means associated with said oscillatory circuit for detecting and amplifying said radio signals.

8. In a system for the reception of radio 50 signals comprising an antenna, a wave conductor connected in series with it, the said wave conductor consisting of a solenoidal coil, a grounded metal plate in close proximity to the said solenoidal coil, the inductance and capacity per unit length and the length of the said wave conductor being adjustable to insure the development of an odd multiple of quarter wave lengths of the signals desired to receive, establishing there- 55 by a stationary wave, electrical leaks connected to ground at nodal points of said stationary wave, a tuned oscillatory circuit placed in operative relation to the extreme open end of the said wave conductor, and means connected to the said tuned oscillatory 60

circuit for detecting and amplifying said radio signals.

9. In a system for the reception of radio 70 signals comprising an antenna which is grounded through an impedance, a wave conductor connected to the antenna at the junction point where the antenna connects to the said impedance, the said wave conductor consisting of a solenoidal coil, a grounded metal plate in close proximity to the said solenoidal coil, the inductance and capacity per unit length and the length of the said wave conductor being adjustable to insure the development 75 of an odd multiple of quarter wave lengths of the signals desired to be received, establishing thereby a stationary wave, electrical leaks connected to ground at the nodal points of said stationary wave, a tuned oscillatory circuit placed in operative relation to the extreme open end of the said wave conductor, and means connected to the said tuned oscillatory circuit for detecting and amplifying 80 said radio signals.

10. In a system for the reception of radio 85 signals comprising an antenna which is grounded through a resistance, a wave conductor connected to the antenna at the junction point where it connects to the said resistance, the said wave conductor consisting of a solenoidal coil, a grounded metal plate in 90 close proximity to the said solenoidal coil, the inductance and capacity per unit length and the length of the said wave conductor being adjustable to insure the development 95 of an odd multiple of quarter wave lengths of the signal desired to be received, establishing thereby a stationary wave, electrical 100 leaks connected to ground at the nodal points of said stationary wave, a tuned oscillatory circuit placed in operative relation to the extreme open end of the said wave conductor, and means connected to the said tuned oscillatory circuit for detecting and amplifying 105 said radio signals.

11. In a system for the reception of radio 110 signals comprising an antenna which is grounded through an impedance, a wave conductor connected to the antenna at the junction point where the antenna connects to the said impedance, the said wave conductor consisting of a solenoidal coil, a grounded metal plate in close proximity to the said solenoidal coil, the inductance and capacity per unit 115 length and the length of the said wave conductor being adjustable to insure the development 120 of an odd multiple of quarter wave lengths of the signals desired to be received, the adjustment being effected by the variation of the distance separation of said 125 grounded metal plate from said wave conductor, establishing thereby a stationary wave, electrical leaks connected to ground at the nodal points of said stationary wave, a tuned oscillatory circuit placed in operative relation to the extreme open end of the said 130

wave conductor, means connected to the said tuned oscillatory circuit for detecting and amplifying said radio signals.

12. In a system for the reception of radio signals comprising an antenna which is grounded through a resistance, a wave conductor connected to the antenna at the junction point where it connects to said resistance, said wave conductor consisting of a solenoidal coil, a metal plate grounded through a variable condenser and in close proximity to said solenoidal coil, said wave conductor being adjustable by means of said variable condenser to insure the development of an odd multiple of quarter wave lengths of the signal desired to be received, establishing thereby a stationary wave, electrical leaks connected to ground at the nodal points of said stationary wave, a tuned oscillatory circuit placed in close operative relation to the extreme open end of said wave conductor, and means connected to said tuned oscillatory circuit for detecting and amplifying said radio signals.

13. In a system for the reception of radio signals comprising an antenna, a wave conductor connected thereto, and a receiving circuit system electrically associated with said wave conductor, said wave conductor being adjustable for the purpose of obtaining the maximum degree of potential of the wave development thereupon of the desired signal.

14. In a system for the reception of radio signals comprising an antenna, a wave conductor connected thereto, and a receiving circuit system electrically associated with said wave conductor, said wave conductor being adjustable for the purpose of obtaining the maximum degree of potential of the wave development thereupon of the desired signal, said wave conductor comprising a solenoidal coil placed in proximity to a grounded metal plate.

15. In a system for the reception of radio signals comprising an antenna, a wave conductor connected thereto, and a receiving circuit system electrically associated with said wave conductor, said wave conductor being adjustable for the purpose of obtaining the maximum degree of potential of the wave development thereupon of the desired signal, said wave conductor comprising a solenoidal coil placed in proximity to a grounded metal plate, the adjustment of said wave conductor being effected by varying the separation distance between said plate and coil.

16. In a system for the reception of radio signals comprising an antenna, a wave conductor connected therewith, the said wave conductor being adjustable with relation to the wave length of the signal to be received, and a receiving circuit electrically associated with said wave conductor.

17. In a system for the reception of radio signals comprising an antenna, a wave con-

ductor connected therewith, the said wave conductor being adjustable with relation to the wave length of the signal to be received, and a receiving circuit electrically associated with said wave conductor, said wave conductor comprising a solenoidal coil placed in proximity to a grounded metal plate.

18. In a system for the reception of radio signals comprising an antenna, a wave conductor connected therewith, the said wave conductor being adjustable with relation to the wave length of the signal to be received, and a receiving circuit electrically associated with said wave conductor, said wave conductor comprising a solenoidal coil placed in proximity to a grounded metal plate, the adjustment of said wave conductor being effected by varying the separation distance between said plate and coil.

In testimony whereof I affix my signature.
